UNITED STATES PATENT OFFICE.

JOHN MURRAY, OF LONDON, ENGLAND.

AUTOMATIC FEEDING MECHANISM FOR BOOK-SEWING MACHINES.

Application filed December 27, 1920. Serial No. 433,524.

To all whom it may concern:

Be it known that I, JOHN MURRAY, a subject of the King of Great Britain and Ireland, and a resident of Hatton Garden, 5 E. C., London, England, have invented certain new and useful Improvements in Automatic Feeding Mechanism for Book-Sewing Machines, of which the following is the specification.

10 The invention relates to book-sewing machines of the kind for securing together by a series of stitchings across their backs series of assembled signatures to form books; and has for its object to provide mechanism for 15 automatically feeding successive signatures and for presenting them to the sewing device and also for applying adhesive to their back edges.

15 In the type of sewing machines to which the invention relates, each successive signature is laid over a bar or frame entered at its centre, the two portions hanging down one on either side of the bar. The bar is then moved to the sewing device and the signature 20 is presented back uppermost to the needle.

25 Hitherto successive signatures have been placed on the presenting bar by hand. According to the invention means are provided for withdrawing them one by one from a supply presented to this device by mechanism hereinafter described, and for 30 positioning them upon the bar ready for presentation to the needle, or to the equivalent mechanism in other types of sewing or equivalent machines. These means consist of a cylinder (or segment thereof) on an axis transverse to the signatures and against which the signature to be removed 35

40 is held with its back downwards. This cylinder is provided with valve-controlled suction devices of the type common in rotary printing machines for manipulating sheets, which devices are adapted to engage 45 top and bottom edges of the signature. Means are provided for firstly rotating the cylinder so as to withdraw the adjacent signature from the supply and so as to move it beyond the presenting bar which is arranged 50 parallel with the axis of the cylinder and so that at the lowest point of its travel from the needle the bar is adjacent to the cylinder. When the cylinder reached this point its motion is reversed, causing the 55 outer half of the signature to fly outwards and beyond the presenting bar. The re-

verse motion is continued until the signature lies upon the bar, the valves of the suction devices are then closed and the signature is left upon the bar. The cylinder 60 may then continue to rotate reversely to the position to engage another signature, or may complete its rotation in the original direction for the same purpose.

According to the invention adhesive is 65 applied to the back edges of the successive signatures before they are taken by the cylinder by which they are fed to the presenting bar. While by this means much neater work and more perfect adhesion of the signatures to one another is assured than heretofore, it is essential that the outer back edges of the first and last signature of each 70 set should not receive adhesive—else adjacent books will adhere to one another. 75

The adhesive is applied to the back edge of the signature, immediately before it is seized by the cylinder, by a roller the axis of which is parallel with the axis of the cylinder and which reciprocates between 80 that cylinder and a doctor roller supplying adhesive. The adhesive-applying roller is reciprocated by any convenient mechanism operating in such consonance with the cylinder that it applies the adhesive to the signature immediately before the latter is seized by the cylinder, and in the train of gearing operating this mechanism (and in which there is preferably provided change 85 wheels or equivalents for varying numbers 90 of signatures forming a book) is a trip mechanism or hit-and-miss device operated by a cam or equivalent and adapted to arrest the adhesive roller when the first and last signatures are being handled. 95

The signatures are presented to the pneumatically-controlled cylinder with their back edges downwards by a device consisting of a conveyor band or the like upon which they are stacked by hand and along 100 which they are fed between register-preserving devices. It is essential that the signatures should not be presented to the cylinder either too loosely or with too great pressure, and means are provided for automatically correcting the rate of feed and so for maintaining correct pressure of presentation.

According to the invention the conveyor 110 is driven through any convenient gearing at a normal speed less than what is actually necessary, but capable of attaining a speed

in excess of normal. Clutch, ratchet, or equivalent mechanism in this gearing is controlled either directly or through a mechanical relay by a spring controlled finger having 5 a portion of small area bearing upon the foremost signature. If the signatures be too loose, then this finger being of small area sinks somewhat into the surface and retains disengaging mechanism out of contact with 10 the clutch, ratchet, or like mechanism. When a certain pressure is attained, however, the finger no longer sinks into the surface of the signature but is moved, and in moving rethrows the disengaging mechanism and reduces the speed at which the conveyors are 15 driven to normal.

An example illustrative of one method of carrying out the invention as applicable in connection with a machine for what is known 20 as "French sewing" (the apparatus being however readily adaptable to other types of sewing or equivalent machines) is shown on seven accompanying sheets of explanatory drawings. Of these Figure 1, Sheet 1, Figure 25 1^A, Sheet 2, Figure 2, Sheet 3, and Figure 3, Sheet 4, are general views of the machine as a whole in plan, side elevation and end elevation respectively; Figures 4, 5, and 6, Sheet 5 are side elevations on an enlarged 30 scale showing in detail the suction withdrawing device and gluing apparatus; Figures 7 and 8, Sheet 6, are side elevations on an enlarged scale of the automatic feeding mechanism; and Figure 9, Sheet 7, is an end 35 elevation corresponding to Figure 7, Sheet 6.

In this example the signatures A to be treated are fed forward in two horizontal piles with their backs downward by automatic means hereinafter described. Adjacent to the ends of the piles and mounted on a transverse shaft B is a cylindrical sleeve C provided with radial arms C¹, C², C³, the latter being in duplicate with each set extending in width between the head and tail 45 dimension of each pile of signatures. For the sake of clearness the operation of the mechanism is described with reference to one only of the two piles of signatures. Secured between the arms C¹ and C³ is a series 50 of arcuate webs C⁵ forming a skeleton periphery against which each signature is held on withdrawal from the pile. Longitudinal channels C⁶ and C⁷ are formed in the arms C² and C³ respectively, and communicating between these channels and the peripheries of 55 the arms is a series of holes C⁸, C⁹. A disc valve D abutting a portion of enlarged diameter at one end of the sleeve C and maintained in air tight contact therewith by 60 springs, controls the admission or air and vacuum to the channels C⁶, C⁷. The vacuum supply is connected to the casing of the valve D by a projecting socket D¹, and has access to the valve face by ports D², D³. The atmosphere is in communication with the face 65

of the valve by way of ports D⁴, D⁵ drilled from the periphery of the valve to meet apertures D⁶, D⁷ in the valve face. The shaft B carries a spur wheel B¹ in mesh with a stud wheel B² which is in turn engaged by 70 a rack B³ which transmits a reciprocating motion to the sleeve C and arms C¹, C², C³. The rack B³ is actuated by a lever B⁴ fulcrumed at B⁵ and carrying a tappet roller engaged by a cam on the main cam shaft E 75 of the machine. The valve D is reciprocated by similar gearing located at the other end of the machine. The modus operandi of the suction device is as follows:—In the position shown in Figure 4 both suction arms C² and C³ 80 are open to the atmosphere via the ports C⁶, C⁸, D⁴, D⁶ and C⁷, C⁹, D⁵, D⁷, respectively. The reciprocating drive for the suction arms and for the control valve is such that a certain amount of lag and lead is provided between 85 the action of the valve and that of the arms at different stages in their motion. Starting from the position shown in Figure 4, the valve first moves relatively to the arms in the direction indicated by the arrow, at the 90 same time cutting off communication between the atmosphere and the arm C³ and making connection between the latter and the vacuum supply by way of the port D². The signature adjacent to the arm C³ will now be 95 seized thereby and simultaneously the arms and valve will rotate as a whole withdrawing the signature from the pile. This movement will continue until the arm C² makes contact with the pile, that is, until it reaches 100 the position formerly occupied by the arm C³, when the valve will rotate relatively to the arms first closing the arm C² to atmosphere and then making connection with the vacuum through the port D². The port D³ 105 is sufficiently long to permit of this relative movement bringing the suction on to the arm C² while the vacuum is still maintained on the arm C³. The arms and valve will now rotate as a whole without further relative 110 movement until the signature is completely withdrawn and the position shown in Figure 5 is reached. The direction of motion is now reversed and arms and valve rotate backwards, initially as one, but after a short 115 traverse the valve again leads and closes communication firstly between the vacuum and arm C² and finally between vacuum and both arms C², C³. This relative movement continues until the position shown in Figure 120 6 is reached, when both arms C², C³ are again opened to atmosphere and the signature is released. Simultaneously with the release the presenting bar T which conveys the signatures one at a time to the sewing 125 machine and there deposits them, has arrived at the position shown in Figure 6 so that the bar T receives the signature as it is released by the suction arms. The path of the bar T lies approximately along the line 130

X, Y, (Figures 4, 5 and 6). After the release of the signature the valve and arms continue to rotate without relative movement between them until they assume their initial position, when the same sequence of operations is carried out upon the next succeeding signature in the pile. The signatures as they leave the conveyor device (hereinafter described) are carried on a plate F located in guides and adjustable longitudinally by means of a screw F¹ to vary the opening F² through which each signature is withdrawn by the suction arms.

According to this example adhesive is applied to the back edges of the signatures one at a time before removal from the pile by the suction arms. The gluing apparatus comprises levers G and H mounted on the fulcrum B⁵ and bearing tappet rollers cam-operated from the main shaft E of the machine. Journalled in the ends of the levers G remote from the fulcrum is a shaft G¹ carrying spur wheels G² in mesh with toothed segments H¹ formed in the ends of the levers H. Rigidly fixed on the shaft G¹ are links G³ the outer ends of which carry a roller G⁴ which acts as the glue-applying roll of the mechanism. The latter is adapted to receive its supply of adhesive from a "doctor" roll G⁵ dipping into a glue-container G⁶ and continuously chain-driven from the cam shaft E. The cams on the shaft E operating the levers G, H, are so designed that the compound motion transmitted to the links G³ transfers the glue roll G⁴ from the position in which it receives its supply from the doctor roll to that in which it applies it to the back edges of the signatures. The function of the levers H in toothed engagement with the shaft G¹ is to effect the actual swing of the links G³ necessary to bring the glue roll into and out of contact with the signatures and with the doctor roll. The levers G, H, are operated in such consonance with the suction device that adhesive is applied to a signature immediately before the latter is seized by the suction arms. In order to ensure that the glue roll G⁴ will rotate when brought into contact with the doctor roll G⁵ and become coated over the whole of its periphery, any suitable known means are provided for driving the roll G⁴ other than by frictional contact with the roll G⁵.

It is essential that the first and last signatures forming a book should not receive a coating of adhesive, otherwise adjacent books would adhere to one another. It will be seen that the actual advance of the glue roll into contact with the signatures is performed by the downward movement of the levers H after the levers G are at the top of their stroke. In order to prevent the operation of the glue roll while the first and last signatures are being handled, there is provided a trip mechanism adapted to in-

terrupt this downward movement of the levers H when the signatures in question are in the normal "gluing" position. This trip mechanism comprises two stops H² located substantially at right angles to the levers H and so supported and guided as to permit of their movement within small limits in a direct line towards or away from projections H³ formed on the underside of the levers H. Normally the travel of the levers H, which are downwardly constrained by springs H⁴ in tension, is in no way interfered with by the stops H², but the latter are adapted to be raised into such a position that they abut the projections H³ on the levers and prevent the downward movement of the latter necessary to swing the glue roll into contact with the signatures. The means for raising the stops H² consists of a roller H⁶ carried on a disc H⁶ mounted on a shaft H⁷ to which is rigidly fixed a ratchet wheel H⁸. The ratchet H⁸ is intermittently rotated by means of a pawl H⁹ pivoted on the outer end of an arm H¹⁰ loosely mounted on the shaft H⁷ and reciprocated by a connecting rod H¹¹ and crank H¹² from the main cam shaft E. The lower ends of the stops H² lie in the circular path of the roller H⁶, and the rate of feed of the ratchet is so arranged that the roller H⁶ intercepts the stops H² and forces the latter upwards, maintaining them thus during the period in which the levers H would normally descend to bring the glue roll into contact with the signatures in the pile. By way of illustration of the operation of this device, suppose the book being constructed to consist of ten signatures, then with a ratchet wheel having say sixty teeth, the pawl H⁹ would take six teeth per revolution of the cam shaft E, the shaft H⁷ rotating one tenth of a revolution for each signature withdrawn from the pile. The rate of feed may be adjusted within small limits by means of a mask J loosely mounted on the shaft H⁷ and angularly adjustable by a set pin J¹ passing through the mask and entered in a fixed bar J² having a number of apertures opposite any of which the mask may be positioned. The effect of advancing the mask J in the direction indicated by the arrow in Figure 4 is to bring the knee J³ thereon into the path of the pawl H⁹ thereby limiting to any desired extent—within the range allowed by the bar J²—the actual amount of rotation of the ratchet caused by each stroke of the pawl. A greater variation in the feed to cope with books containing more varying numbers of signatures may be obtained by substituting a ratchet wheel having a greater or fewer number of teeth, or by actuating the crank H¹² through a series of change gears from the cam shaft E.

The signatures to be presented to the suction apparatus are arranged by hand with

their back edges downwards in two parallel horizontal piles upon two sets of conveyor chains K carried on sprockets K¹. The signatures are fed forward by the chains, and

5 their transverse register is ensured by horizontal guide rails K² transversely adjustable to accommodate different sizes of signatures. In the machine illustrated, automatic feeding means are associated with each set of

10 conveyor chains; to avoid confusion therefore the mechanism will be described with reference to one only of the two piles of signatures. The drive for the conveyor chains is obtained from a spur wheel L loosely

15 mounted upon a shaft M and continuously driven through an intermediate toothed wheel L¹ from the cam shaft E. Mounted on the wheel L is a pawl L² adapted to be thrown into and out of engagement with a

20 ratchet wheel N automatically in accordance with the amount of feed required. The ratchet wheel N is interconnected with the shaft M carrying the chain sprockets K¹ through an epicyclic train of usual form.

25 The train consists of a sleeved extension N¹ on the ratchet carrying a spider in which are located bearings for the planetary wheels N², N³. The wheels N³ mesh with a stationary pinion N⁴, while the wheels N² engage

30 a pinion M¹ fast on the final motion or slow speed shaft M driving the conveyor chains. The pawl L² is provided with a toothed arc in mesh with a toothed quadrant L³ forming a lever centrally fulcrumed on the wheel

35 L and bearing a small roller L⁴ at its end remote from the quadrant teeth. The quadrant L³ is limited in travel by a pin L⁵ attached to the quadrant and passing through an arcuate slot L⁶ in the wheel L. The

40 quadrant and pawl are maintained stable in both the "on" and the "off" position by a spring L⁷ in tension between a fixed point L⁸ on the wheel L and one end of the pin L⁵. It will be seen that the spring acts on oppo-

45 site sides of the fulcrum according as the pawl is in, or out of, engagement with the ratchet. Adjustably secured to a fixed frame O is a ramp O¹ located in the circular path of the roller L⁴ when the pawl is out of en-

50 gagement, but clear of the roller when the ratchet is engaged. Pivoted on the framing is a bell crank lever P one arm of which is located in the path of a projecting finger L⁹ on the pawl L² when the latter is in engage-

55 ment with the ratchet, but clear of the finger when the ratchet is disengaged. The wheel L rotating continuously in the direction indicated by the arrow heads in Figures 7 and 8 carries the roller L⁴ against the station-

60 ary ramp O¹ which throws the feed pawl into engagement with the teeth of the ratchet; this position being shown in Figure 8. The ratchet wheel is then driven forward and with it the conveyor chains until the finger

65 L⁹ is intercepted by the lever P and the pawl again thrown out of engagement, causing an interruption in the feed until the ramp is again reached. Thus the conveyor chains are being advanced only while the wheel L is describing that portion of its revolution located between the ramp O¹ and the lever P. The position of the ramp on the frame O is adjustable in a circular arc to vary the duration of engagement of the pawl. The feed transmitted to the conveyor

70 chains by this period of engagement is such that for each revolution of the cam shaft E the chains are advanced through a distance slightly less than the thickness of a single signature. Trip mechanism is introduced to

75 increase the normal feed of the chains automatically in accordance with the requirements called for by the rate at which the suction withdrawing device operates. The trip mechanism comprises means for withdrawing the lever P out of the path of the pawl finger L⁹ which then continues to make engagement with the ratchet and consequently drives forward the conveyor chains

80 until such time as the automatic means re-

85 throws the lever P into the position in which it interrupts the feed. The signatures as they are fed forward by the chains on to the plate F are pressed against spring fingers Q the lower portions of which making contact

90 with the foremost signature in the pile, being of comparatively small area. The fingers Q are secured at or near the fulcrum of a bell crank lever Q¹ pivoted on a transverse axis Q² in brackets Q³ in the machine frame.

95 A horizontal connecting rod Q⁴ makes operative connection between the depending arm of the lever Q¹ and the vertical arm of the trip lever P. On the opposite side of the lever P from the connecting rod, and colinear

100 with the latter, is a spring Q⁵ in tension between the vertical arm of the lever P and a point some distance to the right thereof. To the outer end of the horizontal arm of the bell crank lever Q¹ is secured a pin Q⁶ located in a vertical slot Q⁷ in the upper end of a vertical rod Q⁸ the lower end of which is operatively connected to a cam lever Q⁹. The lever Q⁹ is fulcrumed at B⁵ and carries

110 a tappet roller engaging a cam on the main cam shaft E, contact between roller and cam being maintained by a spring Q¹⁰ in tension. The mode of operation of the automatic feed control is as follows:—When the suction arms are about to extract the foremost signature in the pile, the lever Q⁹ is lowered by its cam and the bell crank lever Q¹ thus operated to remove the pressure regulating fingers Q from contact with the pile. On complete withdrawal of the signature, the fingers

115 Q are again brought into contact with the pile by the succeeding upward movement of the rod Q⁸ caused by the continual rotation of the cam. It will be seen that as the movement of the fingers is away from the pile, the

120 125 130

consequent movement of the connecting rod Q^4 is in the same direction and does not remove the trip lever P from the path of the pawl finger L^6 . As already explained, the 5 normal feed of the chains corresponding to each revolution of the cam shaft E , that is, to each cycle of the machine, is less than the thickness of each signature. As the latter are withdrawn therefore, the pressure transmitted 10 by the pile to the fingers Q will gradually diminish until the spring Q^5 acting on the rod Q^4 will be able to pull the fingers Q into the face of the pile, and the consequent movement of the rod Q^4 will be sufficient to withdraw the trip lever P from the path of the pawl fingers. The ratchet wheel and consequently the conveyor chains will be driven 15 without interruption until the pressure on the fingers Q has increased sufficiently to re-position the lever P in the path of the feed pawl when the feed will again be reduced to normal. In this way the feed is automatically adjusted in accordance with the rate at which the signatures are withdrawn, 20 thus maintaining at all times a correct pressure on the pile and reducing the liability of fouling to a minimum.

The feeding machine as a whole—that is, the pile conveyors, pressure regulating device, suction withdrawing apparatus and gluing group—is mounted on horizontal rails R along which it is movable to withdraw it from the sewing machine to which it feeds. The feeder is maintained in the 35 correct relative position to the sewing machine by a spring controlled pin R^1 carried from the frame of the feeder and entered in a hole in one of the base members supporting the rails. When the feeder is to be moved, the pin R^1 is withdrawn and the machine moved along the rails, being guided in its motion by a fixed pin R^2 carried from the feeder and located in a horizontal channel R^3 in the base member. The traverse 40 of the feeder along the rails is limited by stops R^4 , one at each end of the channel R^3 . The main cam shaft E of the feeder is driven by worm gearings and spur wheels S^1 from the operating shaft S^2 of the sewing 45 machine.

What I claim is:—

1. In book-sewing machines of the type referred to in which the signatures forming the book are presented to the sewing device 55 upon a signature support, a signature support, automatic means for withdrawing successive signatures from a pile and for positioning them upon the support, said means comprising, a cylindrical member rotatable on an axis transverse to the pile, and against which the signatures are fed with the backs downwards, valve controlled suction devices in the cylinder adapted to engage top and bottom edges of each signature, and means for reciprocating the suc-

tion cylinder and controlling valve means in such relation thereto, and in such consonance with the movement of the signature support, that a signature is withdrawn from the pile on rotation in one direction, and when the motion is reversed, is deposited upon the signature support, substantially as described. 70

2. In the book-sewing machine specified in claim 1, a suction withdrawing device 75 comprising a cylindrical member mounted on a transverse axis and provided with radial arms adapted to engage top and bottom edges of the signature adjacent to the device, arcuate webs secured to the arms and forming a skeleton periphery against which each signature is held on withdrawal from the pile, ports in the radial arms communicating with a valve facing at one end of the cylindrical sleeve, a disc valve abutting this 80 facing and controlling admission of air and vacuum to the ports in the arms, and means for reciprocating the sleeve and the valve in the manner and for the purposes set forth. 85

3. In the book-sewing machine specified in claim 1, means for applying adhesive to the back edge of each signature immediately before withdrawal from the pile, comprising a doctor roll for supplying adhesive, a roller mounted on an axis parallel with that 95 of the suction cylinder and adapted to be reciprocated between the latter and said doctor roll, means for operating the roller in consonance with the suction cylinder, and a trip mechanism adapted to arrest the 100 roller when the first and last signatures of a book are being handled, as and for the purposes set forth.

4. In a book-sewing machine, a cylindrical suction member for transferring signatures 105 to the signature support, an adhesive applying roller, a transverse shaft parallel to the axis of the roller, and links rigid with said transverse shaft for carrying said roller, levers at one end supporting said transverse 110 shaft, and at the other end fulcrumed, a shaft transmitting motion to the suction cylinder, cams thereon operatively connected to said levers at a point intermediate their ends, together with toothed wheels secured to the transverse shaft, levers fulcrumed at one end and terminating at the other end in toothed quadrants engaging said toothed wheels on the transverse shaft, and cam means engaging said levers at 115 points intermediate their ends to impart motion thereto.

5. In a book-sewing machine, a signature support, a cylindrical suction member for transferring signatures to the signature support, an oscillating adhesive applying roller, and trip mechanism for arresting the adhesive applying roller when the first and last signatures of a book are being handled, comprising stop means movable into position 125 130

to halt the movement of the adhesive roller into contact with the signatures, and means, variable in accordance with the number of signatures forming a book, for effecting this 5 arresting movement of the stops, as set forth.

6. In a book-sewing machine of the construction specified in claim 5, a stop control device comprising a ratchet wheel intermittently rotated by a pawl operated from the cam shaft of the machine, a roller moving with the ratchet and so positioned that it engages in its travel the ends of the movable stops and advances the latter to arrest 15 the oscillation of the adhesive applying roller when the first and last signatures are about to be withdrawn, and a mask adjustable in position to vary the rate of feed of the pawl in accordance with the number of 20 signatures forming a book, as set forth.

7. In a book-sewing machine, a suction transfer device, means for feeding the signatures to the suction transfer device, comprising a conveyor adapted to advance the 25 signatures back downwards in a horizontal pile towards the suction device, means for ensuring the transverse register of the pile, means for driving the conveyor, and a regulator of small area bearing upon the fore- 30 most signature in the pile and adapted to regulate the advance by the conveyor in accordance with the pressure exerted by the pile on the finger, as and for the purposes set forth.

35 8. In a book-sewing machine, a suction transfer device, means for feeding the signatures to the suction transfer device, comprising a conveyor adapted to advance the signatures back downwards in a horizontal 40 pile towards the suction device, means for ensuring the transverse register of the pile, means for intermittently advancing the conveyor upon the successive withdrawal of signatures, but to an extent less than the 45 thickness of the signature, and means, controlled by the regulator, for rendering the advance of the conveyor temporarily continuous when the pressure on the pile falls below a predetermined value, as set forth.

50 9. In a book-sewing machine, a suction transfer device, means for feeding the signatures to the suction transfer device, comprising a conveyor adapted to advance the signatures back downwards in a horizontal 55 pile towards the suction device, means for ensuring the transverse register of the pile, means for driving the conveyor, said drive comprising a driving wheel continuously ro-

tated, a ratchet wheel operatively interconnected through reduction gearing with the conveyor, a feed pawl carried by the driving wheel and adapted to be thrown into and out of engagement with the ratchet wheel, a toothed quadrant pivotally mounted on the driving wheel and in mesh with a toothed arc on the feed pawl, a stationary ramp adapted by engagement with the quadrant to throw the pawl into gear with the ratchet, a trip finger adapted by engagement with the feed pawl to throw the latter out of gear with the ratchet, means for stabilizing the pawl in both "engaged" and "disengaged" positions, and means, controlled by the finger, for withdrawing the trip finger from the path of the feed pawl, as and for the purposes set forth.

10. In the combination forming the subject-matter of claim 9 hereof, a depending lever mounted on a transverse axis and carrying the regulating finger bearing on the pile, a connecting rod between the lower end of the depending lever and one arm of a bell crank lever, mounted on a fixed fulcrum and having its other arm normally located in the path of the feed pawl, and a spring in tension between the end of the connecting rod attached to the bell-crank lever and a fixed point in line with the rod but on the opposite side of the lever, as and for the purposes set forth.

11. In a book-sewing machine, a suction transfer device, means for feeding the signatures to the suction transfer device, comprising a conveyor adapted to advance the signatures back downwards in a horizontal pile towards the suction device, means for ensuring the transverse register of the pile, means for intermittently advancing the conveyor upon the successive withdrawal of signatures, but to an extent less than the thickness of the signature, a regulator device, and means, controlled by the regulator device, for rendering the advance of the conveyor temporarily continuous when the pressure on the pile falls below a predetermined value, together with means for releasing the pressure of the regulator device on the pile when the foremost signature therein is about to be withdrawn, said means comprising an arm carried by the regulator device, and a cam operated lever operably connected thereto through a lost motion connection.

In testimony whereof I have signed my name to this specification.

JOHN MURRAY.
